UNITED STATES PATENT OFFICE

BERNARD J. VANDOREN, OF DAYTON, OHIO, ASSIGNOR TO FRIGIDAIRE CORPORATION,
OF DAYTON, OHIO, A CORPORATION OF DELAWARE

REFRIGERATING APPARATUS

Application filed March 31, 1930. Serial No. 440,585.

This invention relates to refrigerating apparatus and more particularly to domestic mechanically cooled refrigerators provided with means for storing and preserving green 5 vegetables or the like.

An object of this invention is to provide the mechanical refrigerator, for instance of the household type, with means for storing green vegetables so that their original crispness 10 may be retained or restored.

Further objects and advantages of the present invention will be apparent from the following description, reference being had to the accompanying drawings, wherein a 15 preferred form of the present invention is clearly shown.

In the drawings:

Fig. 1 is a front elevation of a refrigerator embodying features of this invention;

Fig. 2 is an enlarged cross-sectional view 20 taken along the line 2—2 of Fig. 1;

Fig. 3 is a vertical cross-section taken along the line 3—3 of Fig. 2;

Fig. 4 is a horizontal cross-sectional view 25 taken along the line 4—4 of Fig. 1;

Fig. 5 is a side elevation, with parts broken away and a further enlarged scale, of the receptacle shown in Fig. 2;

Fig. 6 is a side elevation, taken from the 30 rear, of the receptacle and its support;

Fig. 7 is an enlarged front elevation of a portion of the receptacle and its support, and

Fig. 8 is a view in cross section showing another type of receptacle and cover there- 35 for embodying features of the present invention.

A refrigerating apparatus embodying features of this invention may include a refrigerating apparatus, generally designated as 20 which may be a mechanical refrigerator of the domestic type. Thus it may include a mechanical cooling unit, for instance of the evaporator type, generally designated as 21. This unit may be provided with refrigerant 40 which provides temperatures below the temperatures of melting ice. The refrigerator may also include a cooling chamber or compartment 22 which may be provided with one or more shelves 23 and 24. In a structure of this kind air circulates within the

cooling chamber or compartment 22 and passes in contact with the mechanical cooling unit 21. This action reduces the humidity of the air to such an extent that articles placed in the compartment are liable to have an injurious amount of moisture evaporated therefrom. This is particularly true with respect to green vegetables, such as lettuce, celery, radishes, carrots and the like. 55

Means may be provided in the refrigerator 60

for storing such vegetables as those enumerated above, so that their original crispness is maintained or restored. Thus a receptacle 25 may be provided, which receptacle includes a cover 26 so that the circulation of air between the receptacle and the compartment is 65 materially reduced. Preferably the receptacle is adapted to be suspended under one of the shelves, for instance the shelf 23, and for this purpose means for so suspending the receptacle may be provided. This means may include slideways 26a which, if desired, may depend from and be attached to the shelf 23.

Preferably the slideways may be constructed of wire members wrapped around, as shown 70 at 27 and 28, to the front and rear outer wires of the shelf. The wire may be provided with a downward and outward offset 29 permitting the receptacle 25 to slide into and out from under the shelf 23. The receptacle 25 prefer- 75

ably is of sufficient length to accommodate celery, of ordinary length, and of sufficient width and depth to accommodate vegetables such as head lettuce or the like. Thus a receptacle 14 inches in length, 7½ inches in 80 width and 4½ inches in depth has been found 85 satisfactory.

The cover may be, though not necessarily, 90 separate from either the receptacle 25 or the slideways 26a. Preferably the receptacle 25 is provided with an outwardly and downwardly directed flange 30 which is adapted to rest on the slideways 26a. This flange may have its downwardly directed lid cut away at the rear corners as at 32 in order to permit 95 the receptacle to slide along the slideways 26a. Preferably the cover 26 also is provided with a downwardly directed flange 31 adapted to extend around the flange 30 along the slideways 26a and with notches at the rear 100

corners as at 33a. The front of the receptacle 25 may have its flange 30 extended as shown at 35 to form a handle for pulling out the receptacle.

Preferably, the receptacle 25 may be moved or slid in either direction while the cover 26 remains stationary. Thus the outwardly extending flange 31, of cover 26, may be directed upwardly at the front end 33 thereof to thus permit the receptacle 25 to be drawn forward. In order to retain the cover 26 in position while the receptacle 25 is being pulled out, a wire 36 having its ends wrapped around as at 36a and dependnng from the slideways 26a, has been provided. Thus the outwardly extending flange 31, of cover 26, may be directed downwardly to form a curled edge 38 which is placed over the wire 36. Thus the receptacle may be slid in either direction 20 while the curled edge 38 engages the wire 36 to retain the cover 26 in position. The cover may be removed independently of the receptacle by tilting the front end thereof, until the curled edge 38 is above the wire 36, for 25 instance by using the portion 30b of the receptacle as a fulcrum, then removed by sliding same forward.

The receptacle 25 may be removed entirely from under the shelf without removing the cover 26, and it may be reinserted with its flanges 30 between the cover and the slideways 26a by lifting up the front end 33 of cover 26 with the rear portion 30a of flange 30 and then by sliding the receptacle into its 35 proper position. When the receptacle is withdrawn, the flanges 31 of cover 26 will rest on the slideways 26a until the receptacle is replaced as previously described. If desired, the receptacle 25 and its cover 26 may be removed from under the shelf 23 as a unit. This may be accomplished by first moving the rear portion of the receptacle upwardly until the flanged end 38 of the cover is above the wire 36, then drawing the receptacle and its 40 cover toward the front of the shelf until said receptacle and cover are free from the slideways and shelf.

Since some or all of the structures shown are preferably porcelain enameled, it is desirable to prevent contact between the receptacle and the lining 41 of the compartment 22. This may be accomplished by providing a bumper 42 which may be made of rubber and carried by countersunk bolt 44 at the 45 rear of the receptacle 25.

Referring to Fig. 8 there is shown a receptacle 25a which may correspond to the receptacle 25 omitting the rubber bumper. The receptacle 25a is provided with a cover 26b which may be similar to the cover 26. However, the cover 26b is provided with an indented portion 50 which limits the outward movement of the receptacle 25a. Thus when the receptacle is moved outwardly until it 55 reaches a predetermined point which I have

indicated in dot and dash lines, the inside upper rear portion of the receptacle 25a will normally engage the indented portion 50 to thus prevent the entire removal of the receptacle from under the shelf. This is advantageous since it prevents the possibility of the rear portion of the receptacle falling downwardly should the receptacle be unexpectedly moved outwardly too far. However, if desired, the receptacle 25a may be entirely removed from under the shelf by lifting the front end of the cover 26b upwardly until the indented portion 50 clears the receptacle 25a then removing said receptacle by pulling same forward.

Preferably, the receptacle 25a may be moved in either direction on the slideways while the cover 26b remains stationary. In order to retain the cover 26b in position while the receptacle is being moved, the cover 26b may be provided with an outwardly directed flange 38a which may be formed in the shape of a double U having three parallel sides namely, 52, 53 and 54. Thus the flange 38a may be placed over the wire 36 with the parallel sides 52 and 53 on opposite sides of said wire. Thus, when the receptacle is being moved outwardly the side 52 of flange 38a will engage the wire 36 to retain the cover 26b in position. When the receptacle is being moved inwardly the parallel side 53 of flange 38a will engage the wire 36 to retain the cover 26b in position. The parallel side 54 of the flange 38a is adapted to stop the receptacle on its rearward movement when the receptacle reaches its proper closed position. Thus when the outwardly directed curled edge 55 of receptacle 25a engages the parallel side 54 any further rearward movement of the receptacle is prevented since the side 53 of flange 38a will engage wire 36 to act as a stop for the receptacle 25a. Thus it will be noted that the movement of the receptacle 25a is limited in the one direction by the indented portion 50 of the cover 26b and in the opposite direction by the parallel side 54 of flange 38a.

The cover 26b may be removed independently of the receptacle 25a in the same manner as the cover 26 is removable from the receptacle 25. Also, the receptacle 25a and its cover 26b may be removable as a unit in the same manner as the receptacle 25 and cover 26 are removable as a unit.

Ventilating means for providing a restricted circulation between the inner part of the receptacles 25 and 25a and the compartment 22 may be provided. This may be accomplished by providing one or more apertures 40 along the upper part of the receptacles 25 and 25a. In a receptacle of the size above indicated, three holes on each side of $\frac{3}{8}$ inches in diameter have been found satisfactory.

The preferred method of utilizing the re-

ceptacles 25 and 25a for the storing of vegetables is to wash the vegetables and then while a certain amount of free moisture remains on vegetables to place the same in either the receptacle 25 or receptacle 25a under the shelf 23 with the cover over the receptacle. It has been found that with a limited circulation through the ventilating means that the original crispness of the vegetables is retained or restored. The construction preferably is such that with a cooling unit of the float controlled type such as shown in the patent to R. G. Osborn, No. 1,556,708, issued October 13, 1925, and with the cooling unit maintained at substantially 20° F. so that the air circulating around the receptacle 25 is at 45° F. satisfactory results are obtained if the ventilating means permits the daily evaporation of approximately one five-hundredth by weight of the maximum vegetable content of the receptacle 25 or receptacle 25a.

Thus if the receptacles are adapted to contain 5 lbs. of vegetables, with the temperature conditions above indicated it has been found that one one-hundredth of a pound of moisture may be evaporated daily from the contents of the receptacle and that under such conditions the original crispness of the vegetables is retained or restored unless the vegetables have been unduly wilted so that their cells have been destroyed.

While the form of embodiment of the invention as herein disclosed constitutes a preferred form, it is to be understood that other forms might be adopted, all coming within the scope of the claims which follow.

What is claimed is as follows:

1. A refrigerating apparatus comprising a cooling chamber, a shelf therein for articles to be cooled, slideways depending from said shelf, a receptacle slideable on said slideways, a cover for said receptacle supported by said receptacle, and means for retaining said cover in position when the receptacle is being slid.

2. Refrigerating apparatus comprising a cooling compartment, a shelf therein for articles to be cooled, slideways depending from said shelf, a receptacle slideable on said slideways, a cover for said receptacle supported by said receptacle, and means depending from one of said slideways for retaining said cover in position when the receptacle is being slid.

3. A refrigerating apparatus comprising a cooling chamber, a shelf therein for articles to be cooled, slideways depending from said shelf, a receptacle slideable on said slideways and removable therefrom, a cover for said receptacle supported by said receptacle, and means for retaining said cover in position when the receptacle is being slid and said cover resting on said slideways when the receptacle is removed therefrom.

4. Refrigerating apparatus comprising a

cooling chamber, a shelf therein for supporting articles to be cooled, a removable receptacle under said shelf and supported thereby for storage of vegetables or the like, a cover for said receptacle supported by said receptacle, there being ventilation means for providing a restricted ventilation between said chamber and receptacle, and means for retaining said cover in position when the receptacle is being moved.

5. Refrigerating apparatus comprising a cooling chamber, a shelf therein for supporting articles to be cooled, a removable receptacle under said shelf and supported thereby for storage of vegetables or the like, a cover for said receptacle supported by said receptacle, there being holes formed by said receptacle in at least one wall thereof providing a restricted ventilation between said chamber and receptacle, and means for retaining said cover in position when the receptacle is being moved.

6. A refrigerating apparatus comprising a cooling chamber, a shelf therein for supporting articles to be cooled, a movable receptacle under said shelf and supported thereby for storage of vegetables or the like, a cover for said receptacle supported by said receptacle, means for retaining said cover in position when the receptacle is being moved in either direction, and means for limiting the movement of said receptacle in either direction.

In testimony whereof I hereto affix my signature.

BERNARD J. VANDOREN.
